CARL A. CARLSON, OF BRIDGEPORT, CONNECTICUT.

COMBINATION CHAIR AND CRIB.

1,359,671.

Specification of Letters Patent. Patented Nov. 23, 1920.

Application filed July 29, 1920. Serial No. 399,729.

To all whom it may concern:

Be it known that I, CARL A. CARLSON, a subject of the King of Sweden, residing at Bridgeport, county of Fairfield, State of Connecticut, have invented an Improvement in Combination Chairs and Cribs, of which the following is a specification.

This invention has for its object to provide a convertible article of furniture which 10 shall be capable of use either as a chair or as a crib, and which shall be simple in construction and cheap to manufacture, as well as durable, efficient and practical.

With the above and other objects in view, 15 the invention comprises the construction, arrangement and combination of parts as now to be fully described and hereinafter specifically claimed.

In the accompanying drawing forming a 20 part of this specification,

Figure 1 is a perspective view of the article of furniture as when in use as a chair;

Fig. 2 a side elevation on a reduced scale 25 of the article as when set up for use as a crib; and

Fig. 3 is a detail view of one of the rear legs of the article.

10 denotes a chair seat and 11 denotes rear legs therefor which are preferably integrally secured to the seat as shown. The back of the chair, denoted by 12 is supported from the seat by means of strips 13 of material which are secured to the back as indicated at 14 and to the seat as indicated 15 at 15. Chair arms 16, secured to strips 13 of material are held in position by means of chair arm supports 17 secured to the chair arms as indicated at 18 and to the seat as indicated at 19. The chair arms extend 20 forwardly beyond their supports, and to the front end of each, as indicated at 20, crib rails 21 are pivotally secured. Short links 22 pivoted to the front of the seat at its opposite edges, as indicated at 23, are pivoted adjacent their lower ends, as indicated 25 at 24, to long links 25 between which extend slats 26. The crib rails, short and long links, and slats, as well as the chair seat and arms and an end member connecting the 30 forward or lower ends of said crib rails and long links to each other, constitute the frame of the crib. The end member, as shown, preferably comprises bars 27 and rods 28 between the bars. The pivotal connections between the bars and the crib rails 35 and long links can be made in any desirable

manner, said connections being indicated at 29.

Adjacent its front end on its opposite side edges the chair seat is provided with threaded studs 30 adapted to receive wing nuts 31. The front legs of the chair, denoted by 32, are perforated to receive the threaded studs mentioned, and the wing nuts are adapted to hold the front legs to the seat, as will be 60 obvious. Further, each rear leg is provided near its upper end with a similar threaded stud 30 having a wing nut 31. Braces 33, pivotally secured to the lower portions of the front legs as indicated at 34 are provided with suitable perforations to receive 65 the threaded studs near the upper ends of the rear legs, the wing nuts, as before, holding the braces in position.

At or near their extreme lower ends, as 70 shown in Fig. 1, the short links which are pivoted to the front side edges of the chair seat are each provided with headed studs 35, and the long links pivoted to the short links are provided with notches 36 adapted 75 to be entered by the headed studs. Pivoted to each crib rail as indicated at 37 is a link bar 38 provided with a notch 39 each of which is also adapted to engage the beaded studs. Arms 40 pivoted to the chair 80 back as indicated at 41 may carry a table 42 whereby the chair may serve as a high chair. Axles 43 and 44 mounted in the lower ends of the front and rear legs, respectively, are for the purpose of rotatably 85 supporting wheels 45 whereby the article of furniture can be easily transported from place to place. As shown very clearly in Fig. 3, the rear legs are provided with arcuate slots 46 which extend approximately 90 longitudinally of said legs, said slots being equipped in their lower ends with offset portions 47. Springs 48, secured to each rear leg as indicated at 49 and to eyes 50 carried by the rear axle normally hold said axle in 95 elevated position so that the rear wheels of the article of furniture do not rest on the floor, but are positioned as shown in Fig. 1. It will be noted in said figure that the lower ends of the rear legs touch the floor. 100 When it is desired to support the rear legs from the wheels, all that is necessary is to push downwardly on the rear axle and cause it to enter the offset portions of the arcuate slots. To return the rear axle to its elevated 105 position, all that is necessary is to cause said axle to be removed from said offset portion.

Referring to Figs. 1 and 2, it will be seen that each rear leg is additionally provided near its lower end with a threaded stud 30 having a wing nut 31, both for a purpose to be explained.

As hereinbefore mentioned, Fig. 1 discloses the article of furniture as when in use as a chair, a high chair in the present instance. The movable portion of the crib 10 frame, by reason of its weight, is in its lowest position. It will be noticed that the braces which connect the lower portions of the front legs with the upper portions of the rear legs are diagonally disposed in order that the front and rear legs of the chair 15 will be spaced from each other a distance approximately equal to the distance from the front edge to the rear edge of the chair, as is desirable.

20 When now it is desired to convert the chair of Fig. 1 to the crib of Fig. 2, all that is necessary is to lift the end member of the crib frame until the slats between the long links are in alinement with the chair seat.

25 This will cause the headed studs on the short links to engage the notches in the long links, as will be obvious. When now the link bars are swung downwardly so that their notches engage the headed studs, the movable portion 30 of the crib frame will be dependably supported in horizontal position as will be obvious from an inspection of Fig. 2. It will be apparent that the article when used as a

35 crib can not be properly supported by the front and rear legs positioned as when in use as a chair, for the reason that weight placed on the crib frame and to the front of the chair seat would cause the article to be tilted over forwardly. Consequently, the

40 crib is caused to be supported in the following manner. The wing nuts which fasten the front legs and the braces to the chair seat and rear legs, respectively, are unscrewed and the front legs and braces are 45 removed from their studs. The braces are then pivoted to the studs from which the front legs have been removed and the front legs are pivoted to the studs carried by the

50 lower portions of the rear legs, the braces of the chair now becoming in effect front legs 51 of the crib and the front legs of the chair becoming braces 52 between the front and rear legs of the crib, it being understood of course that the front legs and braces of

55 the article of furniture of the invention are of proper lengths with respect to each other and with respect to the rear legs so that the chair and crib will both be disposed in horizontal position when set up as shown and 60 described, and that the front legs of the chair are at the same time of sufficient length to cause the crib to be dependably supported when serving as braces for the crib.

65 When the article of furniture is in use as

a chair, it will be obvious that the space, designated A, may be made to receive the blankets and bed clothing used in connection with the crib, and that these can be so arranged that a suitable leg rest for an occupant of the chair is provided.

What I claim is:

1. An article of furniture adapted to be used either as a chair or as a crib, comprising a chair seat, means by which the seat is supported, chair arms supported above the seat, crib rails pivoted to the chair arms, short links pivoted to the chair seat, long links pivoted to the short links, an end member connecting said crib rails and long 75 links, and means for holding said short and long links in alinement with said chair seat.

2. An article of furniture adapted to be used either as a chair or as a crib, comprising a chair seat, means for supporting said seat, chair arms arranged above the seat, crib rails pivoted to the chair arms, short links pivoted to the chair seat, long links pivoted to the short links, an end member connecting said crib rails and long links and 85 serving as the foot of the crib, and means for holding said long and short links in alinement with said chair, said means comprising a link bar pivotally supported by one of said crib rails and provided with a 90 notch, and a headed stud carried by said short link and adapted to enter said notch.

3. An article of furniture adapted for use either as a chair or as a crib, comprising a chair seat, chair arms arranged above said seat, short links pivoted to the opposite side edges of said seat, long links pivoted to said short links, crib rails pivoted to said chair arms, an end member connecting said crib rails and long links, means for supporting 100 said crib rails and said long and short links in alinement with said chair arms and chair seat, respectively, or for allowing said rails and links to depend from said chair arms and chair seat, and means for dependably 105 supporting said chair and said crib when in use.

4. An article of furniture comprising a chair seat, chair arms arranged above said seat, links pivoted to said chair seat, other 115 links pivoted to said first mentioned links, slats arranged between said links, crib rails pivoted to said chair arms, an end member connecting said other links and crib rails and serving as the foot of the frame of said 120 article of furniture, means whereby said slats and chair seat may be in alinement or said slats may be located below said chair seat whereby said article of furniture may be used either as a chair or as a crib, and 125 means for supporting said article in either of its uses.

5. An article of furniture comprising a chair seat, chair arms arranged above said seat, links pivoted to said chair seat, other 130

- links pivoted to said first mentioned links, slats arranged between said links, crib rails pivoted to said chair arms, an end member connecting said other links and crib rails and 5 serving as the foot of the frame of said article of furniture, headed studs carried by said links pivoted to said chair seat and adapted to engage notches in said other links, link bars carried by said crib rails and provided 10 with notches adapted to engage said headed studs, whereby said slats may be held in alinement with said chair seat, and means for supporting said article.
6. In an article of furniture, a chair seat, 15 chair arms arranged thereover, crib rails pivoted to said chair arms, links pivoted to said chair seat, other links pivoted to said first mentioned links, a link bar carried by one of said crib rails and provided with a notch, 20 and a headed stud carried by one of said links and adapted to rest in said notch in said link bar.
7. In an article of furniture, a chair seat, 25 chair arms arranged thereover, crib rails pivoted to said chair arms, links pivoted to said chair seat, other links pivoted to said first mentioned links, means connecting said other links with said crib rails, and means for holding all of said links in alinement with 30 said chair.
8. In an article of furniture, a chair seat, chair arms, arranged thereover, crib rails pivoted to said chair arms, links pivoted to said chair seat, other links pivoted to said 35 first mentioned links, an end member connecting said other links with said crib rails, and means for holding all of said links in alinement with said chair seat.
9. In an article of furniture, a chair seat, 40 chair arms, arranged thereover, crib rails pivoted to said chair arms, links pivoted to said chair seat, other links pivoted to said first mentioned links, an end member connecting said other links with said crib rails, 45 and means for holding all of said links in alinement with said chair seat, said means

comprising link bars carried by said crib rails and provided with notches, and headed studs carried by certain of said links and adapted to enter said notches. 50

10. In an article of furniture, a chair seat, chair arms arranged thereover, crib rails pivoted to said chair arms, short links pivoted to said short links, an end member pivoted to 55 said long links and crib rails and serving as the foot of the frame of said article of furniture, and means comprising link bars carried by said crib rails and provided with notches and headed studs carried by said short links 60 and adapted to engage said notches for holding said short and long links in alinement with said chair seat.

11. In an article of furniture capable of use as either a chair or as a crib, means for 65 supporting said article when used as a chair, said means comprising fixedly located rear legs, removable front legs, and braces pivotally secured to the front legs and removably secured to the rear legs, and means for supporting said article when used as a crib, said last mentioned supporting means comprising said braces and front legs, said braces acting as front legs for said crib and said front legs of said chair acting as braces for said front 75 legs of said crib, whereby said crib may be dependably supported. 70

12. In an article of furniture capable of use as either a chair or as a crib, means for supporting said chair, said means including 80 front legs to which braces are pivotally connected, said front legs and braces being removable from said chair, and means for supporting said crib, said crib supporting means including said braces and front legs for said 85 chair, said braces for said chair acting as front legs for said crib and said front legs for said chair acting as braces for said crib, as hereinbefore described.

In testimony whereof I affix my signature. 90

CARL A. CARLSON.
